(57) **CLAIM**

The ornamental design for a chair, as shown and described.

DESCRIPTION

FIG. 1 is an upper perspective view of the chair showing my design.

FIG. 2 is a front view thereof;

FIG. 3 is a back view thereof;

FIG. 4 is a side view thereof;

FIG. 5 is an opposite side view thereof;

FIG. 6 is top view thereof;

FIG. 7 is a bottom view thereof; and,

FIG. 8 is another upper perspective view of a second embodiment, the difference being a matter of length.

The chair is a piece of furniture for sitting. The chair in this design is a rocking chair. The embodiments have the same design features, the differences between embodiments being a matter of length.
